UNITED STATES PATENT OFFICE.

ALVIN TAPLIN, OF FORESTVILLE, CONNECTICUT.

MACHINE FOR WASHING ORANGES.

SPECIFICATION forming part of Letters Patent No. 772,441, dated October 18, 1904.

Application filed September 23, 1903. Serial No. 174,297. (No model.)

To all whom it may concern:

Be it known that I, ALVIN TAPLIN, a citizen of the United States, residing at Forestville, in the county of Hartford and State of Connecticut, have invented certain new and useful Improvements in Machines for Washing Oranges, of which the following is a specification.

The invention relates to machines for washing oranges or other fruit; and the objects of the improvement are simplicity and economy in construction and efficiency in operation.

In the accompanying drawings, Figure 1 is a plan view of the machine with the discharging-incline in position to discharge the fruit. Fig. 2 is a broken front elevation of the same with the discharging-incline broken off and turned back out of action. Fig. 3 is a sectional view of the same on the line *xx* of Fig. 1 and with the discharging-incline in the same position as in the said Fig. 1. Fig. 4 is a side elevation of a portion of the said machine, showing the rest or support for the upper end of the discharging-incline on the inner face of one end of the machine.

The framework of the machine comprises four posts 5, two end pieces 6 7, and front and rear rails 8. Upon this frame there is mounted a water-tight trough or vessel 9 of substantially a semicircular form. A cylinder 10, covered with any suitable filamentous brushing-surface 11, is mounted in suitable bearings on the said frame so as to extend downwardly into the trough or vessel 9, as best shown in Fig. 3. If the machine is to be driven by hand instead of by power, the shaft of the cylinder is provided with a crank 12, by means of which the said brushing-cylinder may be rotated. At the side which for convenience is called the "front" of the machine there is a brush-supporting bar 13, which is adjustably held at the ends by bolts 14, that pass through vertical slots 15 in the front posts. At the rear of the machine there is another brush-supporting bar, 16, the ends of which rest upon the rearwardly-inclined upper edges 17 of the two end pieces 6 and 7, which bar is further secured by suspending devices in the form of springs 18, the said springs being secured to the said bar at one end and at the other end

to an eye or other fastening device on the said end pieces, whereby the said brush-supporting bar and this end of the brushing-surface, hereinafter described, is yieldingly held in its position on the said end pieces. A filamentous brushing-surface 19, integral with or mounted on a flexible fabric that constitutes the backing 20 of a sheet or blanket like form, extends nearly around the brushing-cylinder and is supported by the said bars 13 and 16 by being secured directly to the bar 16 at a point to the rear of the extreme end of the said brushing-surface (although the said point is practically at one end of the said brushing-surface considered with reference to its whole length) and by being secured at the other end to the lower ends of the springs 21, the upper ends of the said springs being secured by any suitable means to the supporting-bar 13. It will thus be seen that the flexible brushing-surface, which may be called the "surrounding" brushing-surface, extends nearly around the brushing-cylinder and is yieldingly supported from each end so as to give in an edgewise and lengthwise direction, more or less, within certain limits between the rotary and non-rotary brushes as circumstances may require and without any adjustment, while the front supporting-bar is adjustably mounted in order to change the normal relation of the cylinder and surrounding brushing-surface to adapt the range of the self-adjustment to a general run of larger or smaller fruit—as, for instance, for grape-fruit or oranges. This adjustment of the range makes no difference in the tension of the suspending-springs. There are only three of these suspending devices in the form of springs 21, so that the fabric at the front end is connected to the frame at only three different points, while the portion of the fabric between the said points is left free and unfastened, whereby different points in the width of the fabric will yield differently under the action of the fruit being cleaned.

At the front of the machine is a discharging-incline 22, having a front guide 23, the upper end of the said incline resting on the supporting-ledge 24 on the inner face of the end piece 6, while the other end is secured by a hinge 25 to the end piece 7, the said incline

slanting downwardly to that side or end of the machine which is at the right, as shown in Figs. 1 and 2, and when in its active position substantially filling the space between 5 the moving and stationary brushing-surfaces, as shown in Figs. 1 and 3. When desired to throw this incline out of action, it is only necessary to turn the same on the hinge 25 to change its position from that shown in Figs. 10 1 and 3 to the position shown in Fig. 2. It will thus be seen that the said incline is removably mounted in front of the brushing-cylinder.

The brushing-surfaces both for the rotary 15 and non-rotary brushing may be of a filamentous material and of any ordinary construction for brushing, scrubbing, or scouring devices; but for cheapness and efficiency an ordinary coconut-fiber mat makes a good brushing- 20 surface for the rotary brush and also for the non-rotary brush and its flexible backing. This surrounding brushing-surface extends from a point in front of the brushing-cylinders around under the same and up over the 25 top to or beyond the summit thereof. At the front it is remote from the cylinder to form the open mouth of a pocket to catch the fruit, and it is loosely suspended from the ends, leaving the sides free and with a gradually- 30 converging open space between the outer and inner brushing-surfaces at the front and bottom.

In using the machine the discharging-incline 35 is turned back out of the way, as shown in Fig. 2, and the oranges, fruit, or vegetables are put into the front of the machine at the mouth of the pocket, between the brushing-cylinder and the surrounding brushing-surface. For washing, the trough or vessel should 40 be charged with water. The rotary brush is driven for brushing the fruit or other objects between the two opposing brushes. In so doing the flexible backing of the surrounding brushing-surface and the yielding capacity of 45 the supports for the said surface readily accommodate the brushing-surfaces to fruit having a range of varying sizes, so as to effectually brush the same and also carry the fruit down through the vessel and up over the top of the 50 rotary brushing-cylinder and down on the frontside thereof. If the discharging-incline is out of the way, so as not to intercept the fruit as it falls down the front of the cylinder into the mouth of the pocket, the fruit may 55 be carried around repeatedly until it is thoroughly cleaned. When it is desired to discharge the fruit, the discharging-incline is turned into the position shown in Figs. 1 and 3, and then by the continued rotary movement of the cylinder the fruit is brought to 60 the front and will fall upon the discharging-incline and roll out of the machine into any suitable receptacle that may have been arranged for its reception. Another lot of fruit 65 or other similar rounded objects can then be

placed in the machine and the operation repeated. The objects operated upon are put into the machine and discharged therefrom at the front. They are always carried once around the cylinder, and by leaving the discharging-incline in its idle position they may be carried around the cylinder as many times as may be desired and until they are found to be well cleaned.

In order to clearly distinguish from the prior art, it may be noted that the surrounding brushing-surface in my machine has a filamentous brushing-surface supported on a flexible backing that is preferably in a sheet or blanket like form and is suspended from the frame by only two opposing sides or edges, leaving the other two side edges free from the frame. This differs from the yielding and surrounding brushing-surface of the Phelps *et al.* patent, No. 409,754, for fruit-cleaning machine, in which the brushing-surface is mounted on a series of rigid longitudinal strips forming backs or bodies which are made yielding, but not flexible, by being separately mounted on a hinge at one end, while the other end rests upon a spring. This makes them yielding in the direction that is permitted by the hinged ends, while the backs or bodies are unyielding in every other respect. In my machine the backing being flexible of itself bends in various directions around the side of the orange or similar object pressing toward it, so that the brushing-surface will fit the said side to a greater extent than can a brushing-surface that is mounted on a rigid or wooden backing, as in the said Phelps *et al.* patent.

It is apparent that some changes from the specific construction herein disclosed may be made, and therefore I do not wish to be understood as limiting myself to the precise form of construction shown and described, but desire the liberty to make such changes in working my invention as may fairly come within the spirit and scope of the same.

I claim as my invention—

1. The combination of the frame with the rotary filamentous brushing-cylinder, a surrounding filamentous brushing-surface having a flexible backing, a support for the said backing mounted on the said frame, means for yieldingly connecting the ends of the said brushing-surface with the said support, and means for adjusting the said support on the frame at one of the said ends.

2. The combination of the frame with the horizontally-arranged rotary brushing-cylinder mounted thereon, the surrounding brushing-surface connected with the said frame and extending from a point in front of the said cylinder around under the same and up over the top to the summit thereof, and a discharging-incline removably mounted in front of the said cylinder, whereby the objects being cleaned are entered and discharged from the same side of the said cylinder.

3. The combination of the frame with the rotary brushing-cylinder, a surrounding filamentous brushing-surface having a flexible backing in a sheet or blanket like form and suspending devices for connecting the said surface and backing to the said frame, the said devices being arranged for yielding in the edgewise direction of the said backing.

4. The combination of the frame with the rotary brushing-cylinder, a surrounding brushing-surface having a flexible backing, springs for connecting one end of the said backing with a support on the frame, and means for adjusting the support to which the said springs are secured and means for connecting the other end of the said backing with a support, whereby the space between the outer and inner brushing-surfaces may be changed without changing the tension of the said springs.

5. The combination of the frame with the horizontally-arranged rotary brushing-cylinder, the surrounding filamentous brushing-surface, a flexible fabric forming the backing of the said brushing-surface and extending around the under side of the said cylinder, means for connecting one end of the said fabric to the said frame and a plurality of suspending devices for connecting the other end to the frame, the said devices being arranged at different points in the width of the said fabric with the portion of the said fabric intermediate the said different points being left free to allow the said fabric to yield differently at different points in its width.

6. In a washer, the combination of the frame with the filamentous brushing-cylinder, a surrounding filamentous brushing-surface having a flexible backing and a yielding connection acting in the edgewise direction of the said backing for mounting the said backing on the said frame for yielding edgewise as well as flatwise.

7. The combination of the frame with the horizontally-arranged rotary brushing-cylinder, the surrounding brushing-surface connected with the said frame at the front of the said cylinder, extended around under the same, and up over the top toward the front, leaving an opening where a portion of the cylinder is exposed and a removable discharging device for application to the said opening to intercept and discharge the objects being washed when desired.

8. In a washer, the combination of the frame with the rotary brushing-cylinder, a surrounding brushing-surface having a flexible backing with two ends, yielding connecting devices arranged to act in the edgewise direction of the said backing and serving to connect one of the said ends with the said frame, yielding connecting devices arranged to act in the edgewise direction of the said backing and connecting the other end thereof with a

support mounted on the said frame, and means for adjusting the said support on the said frame.

9. The combination of the frame with the horizontally-arranged brushing-cylinder, the surrounding brushing-surface suspended by one end at the front, a bar connected with the opposite end of the said surrounding brushing-surface with the ends of the said bar slidingly supported at the upper part of the said frame, and springs connected by one end to the said bar and by the other end to the said frame.

10. The combination of the frame with the horizontally-arranged brushing-cylinder, a surrounding brushing-surface in the form of a flexible sheet or blanket extending from the front of the said cylinder down under the same and up over the summit thereof, means for connecting the said surrounding brushing-surface to the said frame at the said front and a supporting device resting on the said frame and connected to the said surrounding brushing-surface on the rear side of the summit of the said cylinder and to the rear of the delivery end of the said surrounding brushing-surface.

11. The combination of the frame with the rotary brushing-cylinder, the surrounding concave consisting of a series of closely-set and substantially radially arranged filamentous material having a flexible backing in the form of a sheet or blanket, yielding devices for loosely suspending the said backing from its ends on the said frame and with its middle portion extending around the under side of the said cylinder leaving a variable working space between the said cylinder and concave, and means for adjusting the said concave to vary the radial width of the said working space.

12. The combination of the frame with the driven brushing-cylinder having a substantially continuous surface of closely-set and substantially radially arranged filamentous material, the surrounding non-driven concave consisting of a continuous series of closely-set filamentous material and a backing of filamentous material made up in the form of a sheet or blanket, flexible in all directions, and means for suspending the said backing from its ends on the said frame with its middle portion extending in a limp form around the under side of the said cylinder with a working space between the said cylinder and concave, the said backing being free to bend in every direction for embracing an extended surface of globular objects as they are rolled through the said working space.

ALVIN TAPLIN.
